UNITED STATES PATENT OFFICE.

GEORGE W. GILL, OF BATTLE CREEK, MICHIGAN.

CAR-COUPING.

1,340,538.

Specification of Letters Patent. Patented May 18, 1920.

Application filed February 8, 1919. Serial No. 275,886.

To all whom it may concern:

Be it known that I, GEORGE W. GILL, a citizen of the United States, residing at Battle Creek, in the county of Calhoun and State of Michigan, have invented certain new and useful Improvements in Car-Couplings, of which the following description, taken in connection with the drawings, forms the specification, the principle of the invention being therein shown and the best mode I have devised for applying the same in practice.

A characteristic feature of the invention lies in so constructing the various parts that the draw-head and all operating elements will be self contained or intact, thereby obviating special fixtures in its attachment to cars and resultant unsatisfactory service occasioned by varying conditions in cars to which the couplers are attached.

An important object of the present invention is a means whereby its knuckle may be released from the locking mechanism in its drawhead when connected with a knuckle of another car in making a running switch, and when the cars are separated leave said unlocked knuckle in position to re-couple. Another object is to construct a coupler so that the knuckle can always be released to connect with an opposite coupler without resorting to pulling said knuckle open with the hands. Another object of the invention is to construct certain of the operative parts with such interchangeability that a novice of ordinary intelligence can assemble the same without error or confusion.

Still another object of the invention is to so construct the knuckle-operating mechanism that the knuckle may be readily released whether during slack or pulling strain; whereby the mechanism will not be subject to foul from snow, sleet or other foreign elements; be compact, durable, positive in operation, simple in construction, economical to manufacture, symmetrical in design, and easy to manipulate. These and other objects and advantages will be more fully defined in the following specification and particularly set forth in the appended claims.

In the drawings forming a part of the specification, Figure 1 is a plan view of an

embodiment of the coupler with the knuckle closed.

Fig. 2 is a front end elevation with the knuckle closed.

Fig. 3, is a broken plan view of Fig. 2 on the line 2.

Fig. 4 is a broken plan view similar to Fig. 3 and shows the knuckle unlocked.

Fig. 5 is a broken plan view similar to Fig. 3 with the knuckle unlocked and the locking slide set to permit the knuckle to open and release an interlocked knuckle of a car shunted at a distance from an operative.

Fig. 6 is a longitudinal sectional side elevation on the line x-x of Fig. 1.

Fig. 7 is a longitudinal sectional side elevation with the locking slide in a rearward position, as in Fig. 5 to permit the knuckle to open.

Fig. 8 is a perspective view of the locking slide.

Fig. 9 is a perspective view of the locking weight.

Fig. 10 is another form of my improved car coupler in longitudinal plan section with the knuckle closed and the operating lever in position preparatory to reacting the locking slide and operating the knuckle-thrower to open the knuckle.

Fig. 11 is a longitudinal plan section with the operating lever in position after having reacted the locking slide and operating the knuckle-thrower to open the knuckle, the dotted lines showing the knuckle at its extreme opening or throw.

Fig. 12 is an enlarged perspective view of the knuckle-throwing lever.

Like marks of reference refer to corresponding parts throughout the different views in which A represents a draw-head having the guard arm 1, a longitudinally-formed rectangular mouth opening 2, a cut-away recess 3 in which the knuckle tail 4 is adapted to oscillate, and a transversely-formed slot 5 through which the reduced end of the locking slide lever 9 may be operated.

The draw-head A and its knuckle B are designed to permit the operation of the coupler with those in general use, the coupler differing only to the rear of the knuckle

and guard arm to permit the application and operation of my improvements.

The knuckle-locking slide 7 is rectangular in cross section and is formed with arc-shaped ends. Preferably the slide is formed somewhat wider in one dimension so that no error can be made in placing the slide within the mouth opening 2 of the draw-head, its arc-shaped ends lying transversely when in operative position to permit the rounded end of the knuckle tail 4 to readily react, push in and pass said slide when the knuckle is turned inwardly. The slide 7 is formed with a longitudinal transverse slot 8 through which the point of the operating lever 9 may play. The faces of the slide designated as its top and bottom have oppositely-disposed slots 10 into which an operating latch 11 may work. As will be obvious, this slide may be inserted into the mouth 2 of the draw-head either end to or either side up and perform the function of its office perfectly.

Below the draw-head a boss 11' is formed, the same having a cylindrical-shaped opening 12 communicating at its top with the mouth 2 in the draw-head by a narrow slot 13, see Fig. 7, in which the operating latch 11 works, said latch operating on a pin 12' to the rear of the cylindrical opening and at or near its top, as shown. This latch is curved, its upper end operating within the slot 10 of the locking slide, its lower extremity working in a slot 13' of a gravity weight 14 loosely suspended on said latch in the cylindrical chamber 12. The weight 14 by preference is formed so that it may be used either end to, so that no error can be made in its operation with the coupler, this being accomplished by forming the slot 13' midway between the ends of the weight, and that friction with the latch 11 may be considerably minimized the ends of the slot are rounded toward the ends of said weight, as shown, the lever being also curved to minimize friction in its action with the weight.

The arrangement of the parts is such that the weight will normally keep the locking-slide 7 forward within the mouth 2 of the draw-head, the slide being moved rearwardly only by the closing of the knuckle-tail 4 or by means of the hand-operating lever 9, the operation of the latter being presently set forth. The hand lever 9 is flattened, and pointed at its end entering the slot 5 of the draw-head, and its outer extremity may be rounded to more freely operate through a neck opening of a yoke 15, the latter of which is of Y formation, the ends striking an offset portion 16 of the draw-head and receiving a vertically-disposed attaching pin 17. The flattened portion of the lever is formed with a longi-

tudinally-disposed slot 18 through which the pin 17 passes, the slot being for the purpose of permitting the lever to have a slight longitudinal play.

In alignment with the slot 5 on the opposite side of the mouth opening in the draw-head, a detent or gain 19 is formed (see Fig. 11). Preferably the detent is curved rearwardly and formed at its forward end to effect a stop or shoulder for limiting the movement of the lever 9 forwardly when thrust within said detent. The office of the detent is primarily for the purpose of holding the locking-slide 7 at a position so that the tail 4 of the knuckle may swing outwardly and permit the knuckle to unfold and release an interlocked knuckle of another coupler when it is desired to push a car, as on a siding, and disconnect when reacted without the presence of an attendant on the spot at which the uncoupling is made.

In the preferred embodiment of my improved coupler I provide a knuckle thrower C, consisting of a curved lever having a transversely-formed slot 20 through which the reduced end of the operating lever 9 passes, the knuckle-thrower occupying a position within the recessed portion of the draw-head in which the lever operates, it being held in position by the pin 17—co-jointly with said operating lever.

The knuckle-thrower is for the purpose of positioning the knuckle so that it will not require the opening of the same by direct hand contact, as is frequently the case with couplers as at present designed, the opening of the knuckle being readily and easily accomplished by grasping the lever 9 and moving the same to the left (as indicated by the arrow in Fig. 9) with a quick action, said opening being effected by the outer tip of the knuckle-thrower C bearing against the rear side of the knuckle tail 4. The slot 20 of the knuckle-thrower is sufficiently broad to permit the lever 9 to have a limited movement before effecting the movement of said thrower. The knuckle-thrower is also formed in such manner that it may be employed either end to in its operation in the coupler.

As will be obvious, the weight 14 in all instances keeps the locking-slide 7 forward in the mouth of the draw-head and the operating lever 9 in position to withdraw said locking-slide as occasion may require, the parts being so designed and arranged that the locking-slide lever and knuckle-thrower will simultaneously act when moved to predetermined contacting position.

From the foregoing description taken in connection with the drawings, it will be obvious that I have devised a car coupler that may be attached to any standard car without especial fittings, be capable of every requirement expected of couplers and fulfill such

requirements without question, obviate strenuous labor in uncoupling cars under load, and by means of gravity force insure positive operation of the knuckle lock in a 5 simple and reliable manner.

To those skilled in the art to which my invention appertains, a more extended explanation of the invention and mode of operation is believed will not be necessary.

10 Having therefore set forth my invention, what I claim as new and desire to secure by Letters Patent, is:

1. In a car coupler, the combination with the draw-head having a pivotally-suspended 15 knuckle opposite the guard arm thereof and formed with a longitudinally-arranged intermediate mouth opening, of a latch pivoted below said mouth opening and extending thereinto, a locking slide operative within 20 said mouth-opening adapted to engage and release said knuckle and engaging with said latch, a weight suspended from said latch to movably hold said locking slide in a forward position within said mouth, said draw-head 25 having a side slot intersecting said mouth-opening thereof, and a lever pivotably movable in said slot for engaging said locking slide to release said knuckle.

2. In a car coupler, the combination with 30 the draw-head having a pivotally-suspended knuckle opposite the guard arm thereof and formed with a longitudinally-arranged intermediate mouth opening, said mouth opening having a chamber opening thereinto 35 from below having a side slot, a curved latch pivoted within said slot, one end thereof extending within said mouth opening, its opposite end extending within said chamber, a locking slide operative within said mouth- 40 opening adapted to engage and release said knuckle and engaging with said latch, a weight within said chamber suspended from said latch to movably hold said locking slide in a forward position within said mouth, 45 said draw-head having a side slot intersecting said mouth-opening thereof, said locking slide having a transversely-formed slot therethrough and a lever pivotably movable in said slot for engaging said locking slide 50 to release said knuckle.

3. In a car coupler, the combination with the draw-head having a pivotally-suspended knuckle opposite the guard arm thereof and formed with a longitudinally-arranged intermediate mouth-opening, of a latch pivoted below and rearwardly of said mouth opening, a reversible locking-slide having convex outer ends operative within said mouth opening, said knuckle having a convex tail end, said slide adapted to close said mouth-opening and preclude said knuckle from opening when closed and to release said knuckle to open when reacted, the convex tail end of said knuckle when open

adapted to bear against the convex outer end 65 of said locking slide and push in and by said slide when moved to close, said draw-head having a side slot intersecting said mouth-opening thereof, and a lever pivotally movable in said slot for engaging said locking slide to release said knuckle.

4. In a car coupler, the combination with the draw-head having a pivotally-suspended knuckle opposite the guard arm thereof and formed with a longitudinally-arranged intermediate mouth-opening, of an interchangeable and reversible locking slide having convex ends operative within said mouth-opening, said slide adapted to close said mouth-opening and prevent said knuckle from opening when closed and to release said knuckle to open when reacted, of a latch pivoted below said mouth-opening and extending thereinto, said latch engaging with said slide, a weight suspended from said latch to normally hold said slide within the exit of said mouth-opening, said draw-head having a side slot intersecting said mouth-opening thereof, and a lever pivotably movable in said slot for engaging said locking 90 slide to release said knuckle.

5. In a car coupler, the combination with the draw-head having a pivotally-suspended knuckle opposite the guard arm thereof and formed with longitudinally-arranged intermediate mouth portion, of a slide having reversible interchangeable convex ends operative within said mouth-opening, means to yieldingly hold said slide forwardly in said mouth-opening, said knuckle having a convex tail end bearing against said slide when said knuckle is closed to prevent it from opening, said draw-head having a side slot intersecting said mouth-opening, and a detent alined with said slot in the side wall of 100 said mouth-opening, a yoke pin-hinged to said draw-head, a lever having a slot and slidably movable in said yoke about said hinge pin, said lever adapted to react said slide and release said knuckle to be opened 105 when drawn on, said detent adapted to engage the point of said lever and temporarily hold said slide and permit said knuckle to open, substantially as set forth.

6. In a car coupler, the combination with the draw-head having a pivotally-suspended knuckle opposite the guard arm thereof and formed with a longitudinally-arranged intermediate mouth-opening, of a locking slide having reversible and interchangeable convex ends operative within said mouth-opening, means to yieldingly hold said slide forwardly in said mouth-opening, said knuckle having a curved tail and bearing against said slide when said knuckle is closed to prevent it from opening, said draw-head having a side slot intersecting said mouth-opening, and a detent alined with said slot in 115 120 125

the side wall of said mouth-opening and having a shoulder and curved rearwardly, a lever slidably pinned to operate in said slot, the point thereof adapted to engage within 5 said detent, said lever adapted to react said slide and release said knuckle to be opened when drawn on and temporarily hold slide and permit said knuckle to open, substantially as and for the purpose set forth.

10 7. In a car coupler, the combination with the draw-head having a pivotally-suspended knuckle opposite the guard arm thereof and formed with a longitudinally arranged intermediate mouth portion, of a locking 15 slide having convex reversible and interchangeable ends and slotted from side to side longitudinally and formed with latch openings in its bottom and top sides, said slide operative within said mouth-opening, 20 said knuckle having its tail or inner end rounded and adapted to bear against said locking slide when said knuckle is closed, said draw-head having a side slot intersecting said mouth opening, and a detent alined 25 with said slot in the opposite side wall of said mouth-opening, a yoke pin-hinged to said draw-head, a lever having a reduced end slidably operative through both said yoke and said slot and adapted to pass in 30 and through the slot in said locking slide and into said detent, said lever adapted to react said locking slide to release said knuckle and also to lock said slide to temporarily hold the same and permit said 35 knuckle to open, substantially as and for the purpose set forth.

8. In a car coupler, the combination with the draw-head having a pivotally-suspended knuckle opposite the guard arm thereof and 40 formed with a longitudinally-arranged intermediate mouth-opening, of a locking slide operative within said mouth-opening and arranged to bear against said knuckle to prevent its opening until reacted, said 45 draw-head having a slot at the rear of said knuckle, a lever entering said slot and adapted to engage said locking slide, a knuckle-thrower fitted within said slot and adapted to bear against said knuckle, a pin 50 fitted through said draw-head and passing through said lever and knuckle-thrower, said lever adapted to react said locking slide to release said knuckle and to operate said knuckle-thrower subsequent to 55 acting said locking slide, and means to normally keep said locking slide, lever and knuckle-thrower at an advanced position within said draw-head.

9. In a car coupler, the combination with 60 the draw-head having a pivotally-suspended knuckle opposite the guard arm thereof and formed with a longitudinally-arranged intermediate mouth-opening, of a locking slide within said mouth opening arranged to

bar the outward movement of said knuckle 65 when said knuckle is closed, said drawhead having a slot to the rear of said knuckle-opening communicating with said mouth opening, a yoke fitted to said draw-head to the rear of said knuckle, a lever longitudinally slidable and having a reduced end passing through said yoke and into said slot and engaging said locking slide, a knuckle-thrower positioned within said slot about said lever, a pin passing through said 70 yoke, knuckle-thrower, lever and draw-head, said knuckle-thrower having one of its extremities arranged to bear against said knuckle and move or throw the same open when said lever has moved said locking 75 slide to clear said knuckle, and means to yieldingly react said locking slide, lever and knuckle-thrower to a normal or forward position within said coupler, substantially 80 as and for the purpose set forth.

10. In a car coupler, the combination with the draw-head having a pivotally-suspended knuckle opposite the guard arm thereof and formed with a longitudinally-arranged intermediate mouth-opening, of a locking slide within said mouth-opening, said knuckle having a tail with a convex end, said locking slide having reversible interchangeable convex ends and adapted to bar the outward movement of said knuckle 95 tail when said knuckle is closed, said locking slide having transversely-disposed slots longitudinally therethrough, said draw-head having a slot in alinement with a slot in said locking slide, a yoke fitted to said draw-head at the rear of said knuckle, a lever having a reduced end with a slot passing through said slot in said draw-head and engaging within a slot of said locking slide, a knuckle-thrower positioned within the slot of said draw-head about the reduced end of said lever, a pin passing through said yoke, knuckle-thrower, the slot in said lever and draw-head, said knuckle-thrower 100 arranged to bear against the tail of said knuckle when said lever has moved said locking slide to clear said knuckle-tail and move said knuckle outward, and means to react said locking slide, lever and knuckle-thrower, substantially as and for the purpose set forth.

11. In a car coupler, the combination with a draw-head having a boss depending from its under side and formed with a cylindrical opening and a rearwardly-slotted offset, a reversibly ended weight having a central slot with rounded end walls, and a latch pivotally suspended in said slotted offset and having a curved end engaging within said slot, substantially as, and for the purpose set forth.

12. In a car coupler, the combination of a draw-head having a rectangular-shaped

longitudinally-formed mouth-opening, a locking slide having interchangeable and reversible arc-shaped ends and formed with an intermediate transversely-arranged slot 5 and with oppositely-disposed latch openings, a knuckle having a tail extremity with an arc-shaped end pivoted to said draw-head at one side of said mouth-opening and

adapted to press back and pass said locking slide in the closing of said knuckle, substantially as and for the purpose set forth.

GEORGE W. GILL.
